(57) **CLAIM**

The ornamental design for a lower portion of a baby bottle, as shown and described.

DESCRIPTION

FIG. 1 is a front perspective view of a lower portion of a baby bottle;

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof;

FIG. 6 is a bottom plan view thereof; and,

FIG. 7 is a front perspective view thereof, shown in use. The broken lines shown in the drawings illustrate portions of the lower portion of a baby bottle that form no part of the claimed design.

1 Claim, 3 Drawing Sheets
